UNITED STATES PATENT OFFICE.

JAMES S. RAY, OF EAST HADDAM, CONNECTICUT.

DESIGN FOR THUMB-SCREW HEADS.

Specification forming part of Design No. **8,036**, dated February 2, 1875; application filed January 12, 1875.
[Term of Patent 7 years.]

To all whom it may concern:

Be it known that I, JAMES S. RAY, of East Haddam, in the county of Middlesex and State of Connecticut, have invented an Improved Design for Thumb-Screw Heads; and I do hereby declare that the following is a full, clear, and exact description thereof, reference being had to the accompanying drawing forming part of this specification.

My invention relates to a thumb-screw for use on coffin-lids and other articles.

The nature of my design is fully represented in the accompanying drawing, in which—

Figure 1 is a perspective view of my improved screw-head. Fig. 2 is a central longitudinal section of the same.

The head is of circular form in all its sections taken perpendicular to the axis. The

portion outside of and below the circular line *a a* forms no part of the design, which is limited to the configuration of the top of the head. Within the circular line *a a* is a cavity, *b*, of nearly semicircular profile, which forms an essential feature of the design. This cavity unites in an angle at *c* with a cavity, *d*, which is of a cavetto-like character, above which is a knob, *g*, of spherical form.

I claim as my invention—

The design of the top of the screw-head, substantially as described, and shown in the accompanying drawing.

JAMES S. RAY.
